US0D1059051S

(12) **United States Design Patent** (10) Patent No.: **US D1,059,051 S**
(45) Date of Patent: ** Jan. 28, 2025

(54) **VANITY MIRROR**

(71) Applicant: **simplehuman, LLC**, Torrance, CA
(US)

(72) Inventors: **Frank Yang**, Rancho Palos Verdes, CA
(US); **Tzu-Hao Wei**, Hacienda Heights,
CA (US); **Daniel Ballou**, Long Beach,
CA (US)

(73) Assignee: **simplehuman, LLC**, Torrance, CA
(US)

(**) Term: **15 Years**

(21) Appl. No.: **29/913,283**

(22) Filed: **Sep. 28, 2023**
